WINDOW SHADE HOLDER

Archie C. Cavedo, Durham, N. C.

Application December 3, 1936, Serial No. 114,056

1 Claim. (Cl. 156—24)

This invention relates to a window shade holder and it primarily aims to provide a novel means which will prevent the shade from blowing out into the room when the adjacent window is raised, and will also allow privacy in the room at the same time, although permitting slight clearance to provide for circulation of air.

Various additional objects and advantages will in part be pointed out hereinafter and otherwise 10 become apparent from a consideration of the description following taken in connection with accompanying drawing illustrating an operative embodiment.

In said drawing:—

15 Figure 1 is a perspective view showing my improvements embodied at the lower portion of a window, and

Figure 2 is an enlarged detail perspective view 20 of a fragment of a window and shade illustrating the use of my improvements.

Referring specifically to the drawing wherein like reference characters designate like or similar parts, 10 designates a conventional window frame associated with which is a shade 11 of textile 25 fabric or other flexible material usually rolled on a roller fastened at the top of the window and adapted to be raised and lowered. The lower end portion of the shade is formed into a loop 12 in which a wooden strip 13 is removably placed 30 as usual.

In accordance with the invention, holders are employed comprising walls 14 which are attached to the side stiles 15 of the window frame on the interior of a building, through the medium of 35 flanges 16 and screws or other fastenings 17 passing therethrough, it being realized that the holders are made in right and left hand ones since the flanges 16 should extend in opposite directions for right and left hand use as shown in Figure 1.

40 Integral with the walls 14 and at the upper forward ends thereof are hooks 18 open at the

bottom at 19, the forward edges of the walls 14 being curved as at 20 and merging into the throat of the hook.

To adapt the shade for co-action with the hooks, studs are provided thereon at 21 and the same 5 may be ordinary nails driven into the wooden strips 13.

As a result of the construction described, the shade 11 when in lowered position will be retained therein by pulling the shade down until the studs 10 21 engage the edges 20 and the shade is permitted to retract so that the studs enter the openings of the hooks 18 and are retained therein. In this position, it will be realized that the shade cannot be blown in or out of the window and thus privacy 15 is insured, when the sashes of the window or the sash adjacent the shade 11, is open. It will also be realized that a slight space such as is shown at 22, is left between the window sill and the lower edge of the shade, for ventilating purposes, 20 although not enough to interfere with privacy.

Various changes may be resorted to provided they fall within the spirit and scope of the invention.

I claim as my invention:—

25 In combination with a window shade having a strip adjacent the lower edge thereof, studs secured to said strip and extending laterally beyond the same, means providing hooks open at the lower ends and engageable by said studs to retain the shade against movement, said means being walls disposed at substantially a right angle to the plane of the shade, said walls having elongated forward edges extending upwardly and forwardly and leading to the slots of the hooks, 30 whereby the studs will be guided by such edges into said slots, said hooks having their bills extending inwardly and attaching flanges extending angularly from said walls.
